GEORGE A. JOHNSON, OF CHICAGO, ILLINOIS, ASSIGNOR TO WILLIAM H. MINER, OF CHAZY, NEW YORK.

SHOCK-ABSORBING MECHANISM.

1,290,220.

Specification of Letters Patent.

Patented Jan. 7, 1919.

Application filed March 12, 1913. Serial No. 221,905.

To all whom it may concern:

Be it known that I, GEORGE A. JOHNSON, a citizen of the United States, residing at Chicago, in the county of Cook and State of Illinois, have invented a certain new and useful Improvement in Shock-Absorbing Mechanisms, of which the following is a full, clear, concise, and exact description, reference being had to the accompanying drawings, forming a part of this specification.

This invention relates to improvements in shock absorbing mechanisms.

The object of the invention is to provide a friction shock absorbing mechanism, more particularly designed for railway draft riggings wherein all the parts may be relatively cheaply manufactured in the form of castings and whereby a large frictional wearing area is obtained to produce high capacity.

In the drawings forming part of this specification, Figure 1 is a part elevational view, part longitudinal, vertical section of a portion of a railway draft rigging showing my improvements in connection therewith. Fig. 2 is a vertical, transverse, sectional view, taken substantially on the line 2—2 of Fig. 1. Fig. 3 is a view corresponding to Fig. 1, but illustrating another embodiment of the invention.

In said drawings and referring first to Figs. 1 and 2, 10—10 denote the draft sills of the car to which are secured front and rear stops 11 and 12. The draw bar 13 is operatively connected to the shock absorbing mechanism proper by any suitable means, such as the yoke 14, and the parts may be supported by a detachable saddle plate 15.

The shock absorbing mechanism proper, as shown, comprises front and rear followers A—A', four wedges B—B, a pair of friction members C—C, bolts D—D and springs E—E.

The followers A and A' are duplicates and each is provided on its inner face with a pair of inwardly extending arms 16 and 17, said arms being spaced and located centrally of the followers. The arms 16 and 17 are so arranged that when the two followers A and A' are properly positioned, the arms will be overlapped, although it is not intended that there be any frictional engagement between the overlapped arms themselves. The length of the arms 16 and 17 is made such that they are adapted to limit the relative approach of the followers A and A' when the total per-

missible compression of the gear has been attained.

Each of the wedges B is of substantially right triangular cross section and has a wedge face 18, the wedges B—B being arranged in pairs, two on the inner face of each follower with their wedge faces 18 extended in opposite directions. As will be understood, the wedge blocks B are formed as castings separate from the followers A and A' and are applied as most clearly shown in Fig. 1. When so applied, it is evident that the wedges B—B will frictionally engage the upper and lower surfaces of the arms 16 and 17. The wedges B which are associated with the rear follower A' will, of course, remain immovable with respect to the arms 16 and 17 formed integrally with the follower A', but said wedges will slide relatively to the arms 16 and 17 of the front follower A.

In a corresponding manner, the wedges B associated with the front follower A will frictionally engage the arms 16 and 17 of the rear follower A'. Due to the fact that there is no relative sliding movement between the wedges B and the arms of the corresponding follower, the arms of both followers are preferably reduced in cross section, as indicated at 19—19 at the portions adjacent the followers proper. By this means, as the arms 16 and 17 attached to the front follower A, are worn down at their rear ends due to their sliding contact with the rear set of the wedges B, the wedges B may take up the wear by gradually moving toward the axis 90 of the gear and without interference from the arms 16 and 17 attached to the rear follower A'. The same is true of the front set of wedges B and the front ends of the arms 16 and 17 of the rear follower A'. As will be understood, the reduced sections 19 of the arms 16 and 17 need be extended only to a point slightly beyond the inner edges of the wedges B—B.

The friction members C—C are beveled or wedge-shaped at their front and rear ends, as indicated at 20—20, so as to coöperate with the wedge faces 18 of the wedges B—B. With the arrangement shown, it is evident that upon relative approach of the followers A and A', the members C—C will be separated and in a line at right angles to the axis of the gear.

To resist this separation and thereby absorb the shocks, the bolts D—D are extended

through suitable aligned perforations in the friction members C—C and corresponding recesses 21 provided in the arms 17—17 of the followers A—A' and on said bolts D are mounted the springs E between lower followers 22 and upper followers 23. The bolts D—D are disposed on opposite sides of the yoke so as to avoid cutting away any of the metal of the latter and the upper spring followers 23 are provided with sleeve extensions 24 so as to engage the under side of the lower friction member C. As the friction members C—C are separated, it is evident that the lower spring followers 22 will be elevated and simultaneously therewith the upper spring followers 23 will be depressed so that the compression movement of the springs E is double the travel of the followers A—A', thereby enabling me to obtain a high capacity.

In the structure shown in Fig. 3, the followers A² and A³ are arranged with their inwardly extending arms 116 and 117 one above the other instead of being spaced apart horizontally, as shown in Figs. 1 and 2. In this construction, the inner arms 116 are provided with opposed elongated slots 121 to accommodate a transversely extending bolt D', said bolt D' being extended through suitable slots in the draft sills and having springs E' mounted thereon outside of the sills in a well known manner. In this construction, the wedges extend vertically on either side of the arms 116 and 117 and the friction members are forced apart in a horizontal direction instead of vertically, as shown in Figs. 1 and 2. Detailed discussion of the specific structure is believed unnecessary, since the arrangement of parts in operation is the same as for the structure shown in Figs. 1 and 2, except that a single bolt with springs at each end outside of the sills is substituted for the vertically extending bolts in springs shown in Figs. 1 and 2.

I claim:

1. In a friction shock absorbing mechanism, the combination with relatively movable followers, of centrally disposed friction members extending inwardly from each follower and movable in unison therewith, said friction members being overlapped, wedges on the inner face of each follower, the wedges of one follower frictionally engaging the friction members movable with the opposed follower, outer friction members coöperable with said wedges, and spring means acting through said outer friction members for resisting relative approach of the followers.

2. In a friction shock absorbing mechanism, the combination with a pair of followers relatively movable and each having an integrally formed inwardly extending arm, of a pair of wedges mounted on the in-

ner face of each follower, the wedges on one follower being arranged to frictionally engage the arm of the opposed follower, friction members coöperable with said wedges and adapted to be separated in a line at right angles to the line of relative movement between the followers, and means for resisting separation of said friction members.

3. In a friction mechanism, the combination with a pair of followers each having a pair of spaced inwardly extending arms on its inner face, the arms alternately overlapping each other, of a pair of detachable wedges mounted on the inner face of each follower and adapted to frictionally engage the ends of the arms of the opposed follower when the followers are moved toward each other, friction members coöperable with said wedges, and spring means acting through said friction members for resisting relative approach of the followers.

4. In a friction draft rigging, the combination with draft sills, draw bar and yoke-acting means, of front and rear followers, each follower having an inwardly longitudinally extending arm movable in unison therewith, said arms being overlapped, a pair of wedges detachably mounted on the inner face of each of said followers, said arms and said wedges having coöperating friction faces extending parallel to the axis of the draft rigging, friction members having wedge-shaped ends coöperable with said wedges and adapted to be separated in a line at right angles to the axis of the gear upon relative approach of the followers, and spring means acting through said friction members for resisting relative approach of the followers.

5. In a friction draft rigging, the combination with draft sills, draw bar and yoke-acting means, of front and rear followers, each follower having an inwardly longitudinally extending arm movable in unison therewith, said arms being overlapped, of a pair of wedges detachably mounted on the inner face of each of said followers, said arms and said wedges having coöperating friction faces extending parallel to the axis of the draft rigging, friction members having wedge-shaped ends coöperable with said wedges and adapted to be separated in a line at right angles to the axis of the gear upon relative approach of the followers, and spring means acting through said friction members for resisting relative approach of the followers.

6. In a friction draft rigging, the combination with front and rear followers, each of said followers having a pair of spaced longitudinally extending integral arms, the arms of one follower being alternated with the arms of the other follower, of a pair of

wedges detachably mounted on the inner face of each follower, the wedges of one follower being arranged to frictionally engage the ends of the arms of the opposed follower, ⁵ means permitting said wedges to compensate for wear on the friction surfaces, friction members having wedge-shaped ends coöperable with said wedges and adapted to be separated transversely to the axis of the draft

rigging, a bolt extending through said friction members at right angles to the axis of the gear, and a spring mounted on said bolt adapted to resist separation of said friction members.

In witness that I claim the foregoing I ¹⁵ have hereunto subscribed my name this 28th day of Feb. 1918.

GEORGE A. JOHNSON.
